United States Patent Office

Des. 230,754
Patented Mar. 12, 1974

230,754

TOY TRUCK

Albert C. Oberlander, Box 963, or 323 N. Broadway,
Linton, N. Dak. 58552

Filed Dec. 4, 1972, Ser. No. 311,754

Term of patent 7 years

Int. Cl. D21—01

U.S. Cl. D34—15 AJ

FIG 5

FIG 6

FIG. 1 is a left front perspective view of a toy truck showing my new design;

FIG. 2 is a front end elevational view thereof;

FIG. 3 is a right side elevational view thereof;

FIG. 4 is a rear end elevational view thereof;

FIG. 5 is a top plan view thereof;

FIG. 6 is a bottom plan view thereof.

I claim:

The ornamental design for a toy truck, as shown.
